ELECTRIC CIRCULATING HEATER

Harry F. MacDonald and William N. Askers, Spokane, Wash.; said Askers assignor to H. F. MacDonald and J. C. MacDonald, both of Spokane, Wash.

Application May 8, 1946, Serial No. 668,194

1 Claim. (Cl. 219—38)

1 This invention relates to an air heater and it is one object of the invention to provide an air heater which may be mounted in an air duct through which air is delivered to registers and very effectively heat air prior to discharge through the registers.

Another object of the invention is to provide a heater consisting of a multiplicity of tubes arranged in a bank and through which the air passes, electrically energized heating elements being mounted through the bank of tubes transversely thereof so that the tubes will be heated and air flowing through the tubes warmed.

Another object of the invention is to provide a heater wherein the tubes and the heating units are firmly held together and the bank of tubes supported vertically in an elbow or casing forming part of the air duct.

Another object of the invention is to provide an air heater which is simple in construction and not liable to get out of order.

The invention is illustrated in the accompanying drawings wherein:

Fig. 1 is a sectional view showing a heater of the improved construction mounted in position for use.

Fig. 2 is a top plan view of the heater.

Fig. 3 is a view taken along the line 3—3 of Figure 1.

Fig. 4 is a fragmentary view showing a portion of the heater in elevation.

Fig. 5 is a wiring diagram.

This heater which is indicated in general by the numeral 1 is mounted in an elbow or casing 2 constituting a portion of an air duct through which air flows from a hot air furnace to rooms to be heated. The casing has its lower portion formed at a side with a neck 3 with which an air pipe 4 is connected and at its top the casing is formed with an outlet neck 5 which passes through an opening in a floor 6 and communicates with a hood 7 having gratings or registers 8 at opposite sides so that when the dampers or shutters 9 are opened air may flow into rooms at opposite sides of the partition wall 10.

The heater 1 is formed as shown in Figures 1 and 2 and includes in its construction a multiplicity of tubes 11 which are disposed vertically and arranged in a block, the tubes having confronting side portions welded or otherwise secured to each other. The dimensions of the block of tubes is such that the block fits into the casing 2 in spaced relation to walls thereof and rests upon brackets 12 carried by walls of the casing. Confronting side portions of the tubes are formed with transversely extending openings 13 which register as shown in Figure 4, and form aligned passages through which are passed heating elements 14. These heating elements are electrically energized and of conventional formation 60

and are wired in series so that when a circuit is closed the heating elements or units will heat the tubes and air which flows upwardly through the tubes will be heated. The power wires 15 and 16 are connected with the heating units in the usual manner and in one wire is an electromagnetic switch 17 opened and closed by an electromagnet 18. The wires 19 and 20 for supplying current to the magnet are connected with the power wires and in the wire 20 is introduced a thermostat 21 which closes when room temperature is at a predetermined minimum and opens when the temperature is raised to a predetermined degree. When the switch 17 is closed the heating units will be energized to warm the air flowing through the tubes and when this switch opens the heating units will be deenergized. It will be understood that the number of heating units used is optional and that if so desired heating units extending transversely of the units 14 may be provided.

Having thus described the invention, what is claimed is:

25 An air heater comprising a casing having side walls and a top and a bottom, the top being formed with an outlet opening surrounded by an upstanding neck and a side wall being formed with an inlet opening surrounded by an out-standing neck, brackets in said casing mounted 30 against side walls thereof above the inlet opening, a bank of vertically extending air tubes in said casing spaced from the walls and top of the casing, the tubes being arranged in horizontal rows and the tubes of each row being welded in side by side engagement with each other and in side by side relation to tubes of adjoining rows, contacting side portions of adjoining rows of tubes being formed with vertically spaced side openings disposed in registering relation with 35 companion openings of the said adjoining tubes and providing the said bank of tubes with transversely extending passages, and electrically energized heating units passing through said passages with end portions projecting from opposite 40 sides of the bank of tubes and adapted for connection with conductors.

HARRY F. MACDONALD,
WILLIAM N. ASKERS.
